COMPLETE CIGARETTE CASE

Victoria Trinko, Downers Grove, Ill.

Application September 29, 1947, Serial No. 776,511

5 Claims. (Cl. 312-31.1)

1

The object of the present invention is to provide a complete cigarette case. It is referred to as a complete cigarette case because it constitutes more than a mere holder for cigarettes but adds thereto an ash receptacle, a receptacle for holding a lighter, means for maintaining the mouth portions of the cigarettes in moist condition to thereby keep down throat irritating dust and a stand associated with the lighter receiving compartment in such manner that when the case is in open position it will present a bottom of such wide area as to be easily maintained in an upright position upon a table while at the same time, when folded to closed position it may easily be inserted in the pocket and there be securely held by a suitable clasp.

The invention will be best understood by reference to the accompanying drawing wherein:

Fig. 1 is a perspective view of the case in open position.

Fig. 2 is a partial perspective view of the case in partially open position.

Fig. 3 is a fragmentary sectional view upon a magnified scale of the upper portion of the ash receiving compartment; and

Fig. 4 is a sectional view through the moistening element which also constitutes a closure for the ash receiving compartment.

Like numerals designate corresponding parts throughout the several figures of the drawing.

In the drawing 5 designates a casing dimensioned to receive the cigarettes C with their mouths approximately flush with the top of the receptacle 5. A second receptacle 6 is hingedly connected to the receptacle at 5a and this second receptacle is divided into an ash receiving compartment 7 and a lighter receiving compartment 8. The compartment 8 is intended to receive a conventional lighter for cigarettes, and it is provided with a lid or door 9. This door 9 may be spring actuated to closed position or not, as may be desired. It is hingedly connected to the casing 6 at 10. This door is provided with a conventional latch 11 for holding it in closed position and an outwardly bent spring 12 upon the rear wall of the compartment 8 acts to thrust the lighter (not shown) out of the compartment 8 far enough for it to be readily grasped whenever the door 9 is opened.

The upper portion of the casing 6 constitutes, as stated, an ash receiving compartment. A lid 13 is disposed to cover the ash compartment and when the case is closed this lid lies between the ash compartment and the upper end of the cigarettes. A conventional thumb operated latch 14

acts to keep the lid closed until the latch operating member is pressed. When this latch is released a spring 15 which is secured to the wall of the ash compartment acts to lift the lid far enough so that it may be readily grasped and swung over the cigarettes to thereby permit ashes to be knocked from the cigarettes into the ash compartment 7. The spring 15 serves the double function of initially lifting the lid 13 and of providing a member against which the lighted end of the cigarette may be snubbed to extinguish the same. To this end the spring is made in the form of a small loop indicated at 16. The lid 13 is of novel construction and performs a novel function in that the side toward the ash receiving compartment consists of a thin sheet of metal 13a while upon the side which overlies the cigarettes, when the case is closed, this lid carries a sheet of material 13b of a water absorbent nature, such as, for example, as blotting paper. When this material is wet with water and the case is closed the moist paper overlying the upper ends of the cigarettes dampens the ends of the cigarettes to such an extent that when they are placed in the mouth the likelihood of throat irritating dust being drawn into the throat is greatly reduced.

The lower end of the compartment 6 bears, hingedly connected thereto at 17, an easel leg 18. The length of the leg 18 plus the length of the casing 6 equals the length of the casing 5 and thus when the case is in open position and is rested upon a table a considerable bottom area is presented to maintain the whole in upright position. The casings 5 and 6 are hingedly connected to each other along a pintle 19 and this same pintle may constitute the hinge element for lid 13.

When the case is closed, that is, when 5 and 6 lie in alignment with each other, the case may be placed in a pocket with all of case 5 in the pocket and with the ash receiving compartment in the pocket and with the lighter compartment projecting above the top of the pocket. The case may be held against accidental dislodgment and loss by a conventional type of spring clip 20 which is welded or otherwise secured to the wall of casing 6 at about the line of division between 7 and 8, and along its upper edge only. This permits the lower pointed end to be sprung out enough to engage over the material of the pocket.

A latch 21 is adapted to latch the casings 5 and 6 into alignment with each other when the case is closed to protect the cigarettes and to be placed in the pocket.

A conventional coil spring 22 may be employed to throw the part 5 to open position when latch

21 is released. This spring will then tend to hold 5 and 6 close to each other when the structure is open. Also a spring 23 may be employed to throw the easel leg 18 to open position when a restraining latch button 24 is moved out of restraining position with respect to said leg.

It is to be understood that the invention is not limited to the precise construction set forth but that it includes within its purview whatever changes fairly come within the terms or the spirit of the appended claims.

Having described my invention, what I claim is:

1. A device of the character described comprising a first casing dimensioned to receive cigarettes on end and with their ends substantially flush with the upper end of the casing, a second casing hingedly connected along one side of the first named casing at the upper edge thereof, a lid covering the second named casing in position to lie between said second named casing and the upper ends of the cigarettes when the two casings are swung into alignment with each other, means for holding said lid closed with respect to the second casing and a sheet of water absorbent material upon that side of said lid which faces toward said cigarettes when the casings are moved into alignment with each other.

2. A device of the character described comprising a first casing dimensioned to receive a plurality of cigarettes with their upper ends flush with the upper end of said casing, the upper end of said casing being open, a second casing hingedly connected along its edge to an upper edge of the first named casing, a lid to said second casing having its upper surface covered with absorbent material and having its lower surface of non-absorbent material, said lid being hinged along the line of hinging of the said two casings, one casing being divided into an upper ash receiving compartment and a lower lighter receiving compartment, a spring in the ash receiving compartment tending to lift said lid, said spring being shaped to act as a snubber of cigarettes, means within the second compartment of the second casing adapted to thrust a lighter outwardly from said compartment, a door closing the outer side of the said lighter compartment and adapted to swing downwardly and an easel leg hinged to the second compartment at the lower outer edge of said compartment, the combined length of the two compartments of the second casing and said easel leg being equal to the length of the cigarette receiving compartment.

3. A device of the character described comprising a first casing dimensioned to receive a plurality of cigarettes with their upper ends flush with the upper end of said casing, the upper end of said casing being open, a second casing hingedly connected along its edge to an upper edge of the first named casing, a lid for said second casing, said second casing being divided into an upper ash receiving compartment and a lower lighter receiving compartment, a spring in the ash receiving compartment tending to lift said lid, said spring being shaped to act as a snubber of cigarettes, means within the second compartment

ment of the second casing adapted to thrust a lighter outwardly from said compartment, a door closing the outer side of the said lighter compartment and adapted to swing downwardly and an easel leg hinged to the second compartment at the lower outer edge of said compartment, the combined length of the two compartments of the second casing and said easel leg being equal to the length of the cigarette receiving compartment.

4. A device of the character described comprising a first casing dimensioned to receive cigarettes on end and with their ends substantially flush with the upper end of the casing, a second casing hingedly connected along one side of the first named casing at the upper edge thereof, a lid covering the second named casing in position to lie between said second named casing and the upper ends of the cigarettes when the two casings are swung into alignment with each other, means for holding said lid closed with respect to the second compartment and a sheet of water absorbent material upon that side of said lid which faces toward said cigarettes when the casings are moved into alignment with each other, said second casing being divided into an upper and a lower compartment, the lower of said compartments having its outwardly facing side provided with a door.

5. A device of the character described comprising a first casing dimensioned to receive cigarettes on end and with their ends substantially flush with the upper end of the casing, a second casing hingedly connected along one side of the first named casing at the upper edge thereof, a lid covering the second named casing in position to lie between said second named casing and the upper ends of the cigarettes when the two casings are swung into alignment with each other, means for holding said lid closed with respect to the second compartment and a sheet of water absorbent material upon that side of said lid which faces toward said cigarettes when the casings are moved into alignment with each other, said second casing being divided into an upper and a lower compartment, the lower of said compartments having its outwardly facing side provided with a door, a space within the lower portion of the second casing being shaped to receive a lighter and the rear wall of the lighter receiving space being provided with a spring adapted to thrust a lighter outwardly through said door.
